UNITED STATES PATENT OFFICE.

HERBERT B. TAYLOR, OF PHILADELPHIA, PENNSYLVANIA, ASSIGNOR OF ONE-HALF
TO JAMES TAYLOR, OF PHILADELPHIA, PENNSYLVANIA.

AUTOMATIC RIB-KNITTING MACHINE.

973,236.

Specification of Letters Patent. Patented Oct. 18, 1910.

Application filed July 14, 1908. Serial No. 443,418.

To all whom it may concern:

Be it known that I, HERBERT B. TAYLOR, of the city of Philadelphia, county of Philadelphia, and State of Pennsylvania, have invented certain new and useful Improvements in Automatic Rib-Knitting Machines, of which the following is a specification.

My invention relates to circular rib knitting machines of standard construction and consists in certain improvements therein, hereinafter fully described, which provide for the automatic and simultaneous control not only of the stitch cam of the cam cylinder by which the stitch formed by the vertical needles may be lengthened, but also of a cam of the cam plate by which the radial needles are operated, which are thus made to coöperate in the formation of a loose course which renders the transfer of the work to the needles of another cylinder more easy of accomplishment than in prior machines.

In the drawings, Figure I, is a plan view of the cam box and accompanying parts of an automatic rib-knitter of standard construction embodying my improvements. Fig. II, is an elevation of the same.

Referring briefly at first to those parts common to automatic rib-knitters of this construction, it will be understood that the cam cylinder, which is provided with means for accomplishing its rotation, incloses a stationary needle cylinder (not seen in the drawings) provided with vertically movable needles. Mounted upon the cam cylinder are the standards 2, 2, carrying the yoke 3, from which depends the dial cam plate 4, which is thus rotated simultaneously with the cam cylinder. Beneath the dial cam plate is the stationary dial 5, provided with radially movable needles which coöperate with the vertical needles of the needle cylinder for the production of rib knitting.

Still describing that which is old in the art, it will be understood that the cam cylinder is provided with the usual knitting cams, including a stitch cam, which is vertically adjustable to vary the length of the stitch produced. This stitch cam is connected to a vertical rod 8, which is upwardly spring-pressed and provided upon its upper end with the bevel or cam 9, the position of this rod 8 thus serving to adjust the stitch cam. In order to effect a temporary depression of the rod 8 and therefore of the stitch cam for the production of a loose course,

there is provided a vertically movable post 10, seated in the bed plate of the machine, the vertical position of which is determined by links upon a pattern chain not shown. On the upper end of this post is a large disk 11. When the disk 11 is lifted to the proper level, the rotation of the cam cylinder brings into contact with it a projecting arm 13, fast upon a vertical shaft 14, carried within the cam cylinder and provided with a segmental gear 15, which meshes with a segmental gear 16, on a second vertical shaft 17, also mounted in the cam cylinder, and upon which is fixed a projecting arm 18, on a level slightly above that of the arm 13 upon the shaft 14. The shaft 17, further carries the arm 20, provided at its upper extremity with an adjustable screw 21, the lower end of which when adjusted to the proper level will come into contact with the cam surface 9, on the upper end of the rod 8, and depress it against the tension of the spring which permanently tends to maintain it in the raised position in which it is shown. By the coöperation of these parts when the disk 11, is raised so that it strikes the arm 13, the shafts 14, and 17, are rotated so as to effect the depression of the rod 8, and the corresponding lengthening of the stitch produced by the vertical needles, until a further alteration in the level of the disk 11, occurs, after one or more courses have been knit, by which the disk is put in position to strike the arm 18, and reverse the position of the parts described to their original position, again restoring the stitch to its normal length.

To the parts thus described my invention adds the function of simultaneously lengthening the stitch which is produced by the dial needles. This is accomplished by the following mechanism: The dial cam plate is provided with the usual cams, among which is the pivoted stitch cam 30, which is a draw cam operating to return the dial needles which have been projected by the projecting cam 31, to their normal position. According as this draw cam 30, is moved upon its pivot so that its free end is nearer or farther from the axis of the dial, will depend the distance to which the dial needles are withdrawn after being projected by the cam 31. This draw cam 30, is shown in Fig. I in its normal position to withdraw the dial needles the proper distance for the production of an ordinary stitch, but it is

capable of being moved farther in against the pressure of the needles, and for this purpose it is provided with a vertical pin 33, projecting up above the dial cam plate. 5 An extensible link 34, engages this pin at one end, while its farther end is pivoted to a post 35, set upon the arm 20. The connection of this link 34, with the pin 33, is a slotted one, whereby a certain amount of 10 motion is lost before the movement of the arm 20 drives in the draw cam 30. The extension of the link 34, for the purpose of accurately adjusting the extent to which the motion of the arm 34 moves the draw cam, 15 is accomplished by forming the link of two parts maintained in line by the screw 36, the connection in one of the parts being a slotted one for purposes of adjustment. By the co-operation of the parts thus described, when 20 the disk 11, coming into contact with the arm 13, actuates the arm 20, so as to depress the stitch cam and lengthen the stitch produced by the cylinder needles, it simultaneously throws the free end of the draw cam 25 30, inwardly toward the axis of the machine, increasing the extent to which the dial needles are withdrawn after the formation of their stitches, thereby likewise lengthening the stitches, and thus producing one or 30 more loose courses in which the knitting is of a more open formation than that produced by the hitherto usually employed mechanism, by which the loose course is produced by the operation of cylinder needles 35 only. The knitting of the loose course or courses thus produced will continue until the contact of the disk with the arm 18 reverses the position of the parts, simultaneously restoring both the stitch cam of the cam cylinder and the draw cam of the dial to their normal stitch forming position. The post 10 carries another smaller disk 12, which may be raised to operate cam arms 40 which control the stitch cam for the dial needles for the production of welt courses, but although these parts are shown on the drawing, my invention does not directly concern them and therefore they are not 45 here described, being of known construction. 50 I do not limit myself to the particular means by which operative connection is established between the cams of the cam cyl-

inder and those of the dial cam for simultaneously operating both in the production of a loose course, as other connecting means 55 may be employed.

Having thus described my invention, I claim:

1. In a rib knitter, the combination of the cam cylinder and dial plate each provided with stitch cams; means for altering the position of one of the stitch cams of the cylinder for the production of a loose course; means for altering the position of one of the stitch cams of the dial to coöperate for the 65 same purpose; and connections whereby the operation of one of said cams simultaneously controls the operation of the other.

2. In a rib knitter the combination of the cam cylinder, provided with a stitch cam, 70 and automatically operated means for normally depressing the stitch cam for the production of a loose course; and a dial plate, provided with a movable draw cam, with connections to the means which operate the 75 stitch cam of the cam cylinder by which the depression of the stitch cam of the cam cylinder occasions simultaneous movement of the draw cam of dial plate, whereby both cams coöperate in the formation of a loose 80 course.

3. In a rib knitter the combination of a cam cylinder; means for depressing its stitch cam comprising a rod with a bevel head, a rocking arm which contacts with said bevel head, and means for rocking said arm under the automatic operation of the machine; a dial plate provided with a movable draw cam; and a link connecting said draw cam with the rocking arm, whereby 90 the rocking of the arm to abnormally depress the stitch cam to lengthen the stitch formed by the cylinder needles simultaneously operates the draw cam, so that both said cams simultaneously coöperate in the 95 production of a loose course.

In testimony whereof, I have hereunto signed my name, at Philadelphia, Pennsylvania, this thirteenth day of July 1908.

HERBERT B. TAYLOR.
